INVENTOR
E. L. Minor.

BY ATTORNEY

UNITED STATES PATENT OFFICE.

EDWARD L. MINOR, OF BIRMINGHAM, ALABAMA.

BRICK-CLEANING MACHINE.

1,397,227.

Specification of Letters Patent. Patented Nov. 15, 1921.

Application filed December 18, 1920. Serial No. 431,742.

To all whom it may concern:

Be it known that I, EDWARD L. MINOR, a citizen of the United States of America, residing at Birmingham, in the county of 5 Jefferson and State of Alabama, have invented certain new and useful Improvements in Brick-Cleaning Machines, of which the following is a specification.

This invention relates to a brick cleaning machine and contemplates the provision of a rotatable rack or frame carrying elements which, responsive to centrifugal force, move into position to travel in a path which will cause them to yieldingly engage the surface 10 of the brick or other article to be cleaned while traveling at high speed so as to abrade and rapidly remove the cement and mortar adhering to the surface of the brick without fracturing or defacing the brick.

20 A further object is to provide the rack with a series of loose or floating washers free to have substantial play and when cleaned by centrifugal action to project above the cleaning bed of the machine where 25 they will engage the brick.

A further object is to utilize alternate flat and corrugated washers, the corrugated washers being so staggered about the rack as to cause them, in a complete rotation of the 30 rack, to engage the entire surface to be cleaned.

A further object is to provide the machine with an adjustable bed mounted to rock about the axis of the rack and capable of 35 being set at any desired angle for facilitating the work at hand.

A further object is to simplify the construction by adapting the washers on each rack shaft to project between the washers 40 of the next adjacent rack shafts on each side thereof and thus form the spacer means so as to give the rack a practically continuous abrading surface when spinning at the proper speed.

45 My invention also comprises the novel details of construction and arrangements of parts, which in their preferred construction only are illustrated in the accompanying drawings, in which:—

50 Figure 1 is a vertical sectional view through the machine with the parts in operating position.

Fig. 2 is a plan view of Fig. 1.

55 Fig. 3 is a sectional view taken on the line 3—3 of Fig. 1.

Figs. 4 and 5 are detail end and side views of a cross connection carrying alternating corrugated and flat washers.

Similar reference numerals refer to similar parts throughout the drawings.

In the embodiment illustrated, the machine comprises a center shaft 1 journaled in any suitable bearings 2 with one end overhung to receive a driving pulley 3 driven by any suitable means (not shown). 60 The shaft carries fast thereon a rack formed by spaced disks 4 which are cross connected about their peripheries by bolts 5 which carry spacer sleeves or pipes 6 between the disks. Upon each pipe is assembled a series 70 of hard metal washers 7 with central openings materially larger than the pipes so that they will move outwardly under centrifugal force from half to three quarters of an inch.

The pipes are close enough so that the peripheries of the washers on one pipe will project between the peripheries of the washers on the adjacent pipe on each side and serve as a spacing means for the washers thereon. The washers may be of case 75

hardened steel either flat disks 7 or corrugated disks 7^a, or the washers may alternate flat and corrugated along each pipe with the corrugated washers relatively staggered around the rack so that in a complete rotation of the latter the corrugated washers 85 will engage the entire surface of the article to be cleaned.

The cleaning bed comprises a swinging top frame 8 having downwardly tapering 90 sides 9 which are journaled at an intermediate point on the ends of the shafts 1 and which have their lower ends clamped by bolts 10 which engage in curved slots 11 in the bed sides so that the bed frame can be 95 set at any desired angle. The bed frame is provided with a central aperture 12 through which the top periphery of the spinning washers will project when expanded by centrifugal force.

100 In operation, the rack is driven at a high speed, the washers float outwardly and assume their maximum radius of travel, see Fig. 3, causing them to pass substantially above the top of the bed frame and the articles to be cleaned are then passed across the aperture 12 in the bed frame, thus bringing their under surfaces into contact with the fast spinning yielding periphery of the washer covered rack, with the result that 110

the fast spinning floating washers will act with a most efficient abrading action on the cement or plaster on the bricks and will clean the latter rapidly and effectively.

5 This invention is not intended to be restricted in scope to the specific embodiments shown, but contemplates such modifications as come within the spirit and scope of the claims.

10 Having thus described my invention, what I claim as new and desire to secure by Letters Patent, is:—

1. A rotatable rack having a concentric series of axial supports with floating metal-
15 lic disks mounted thereon, and a bed above which the peripheries of the rotating disks will project to engage an article thereon to be cleaned.

2. A machine in accordance with claim 1, in which the bed frame is adjustable about the axis of the shaft.

3. A machine in accordance with claim 1, in which the disk bearing frame is formed by hard metal plates cross connected by
25 bolts with spacer pipes on the bolts, and a

series of loose washers on each pipe free to have substantial radial movement thereon responsive to centrifugal force.

4. A machine in accordance with claim 3, in which the disks are formed by case hardened metal washers relatively disposed so that the peripheries of the washers on one pipe will project between the washers on adjacent pipe on each side thereof.

5. A machine in accordance with claim 4, in which the washers are of a flat and corrugated type.

6. A machine in accordance with claim 5, in which the flat and corrugated washers alternate on each pipe.

7. A machine in accordance with claim 6, in which the corrugated washers are relatively staggered on the several pipes so that their paths of travel will cover the transverse width of the bed frame opening.

In testimony whereof I affix my signature.

EDWARD L. MINOR.

Witness:

NOMIE WELSH.
